UNITED STATES PATENT OFFICE.

JOSEPH L. KALLUS, OF BROOKLYN, NEW YORK, ASSIGNOR TO JACK COLLINS, OF LOS ANGELES, CALIFORNIA.

DESIGN FOR A DOLL.

Application filed January 6, 1926. Serial No. 15,977. Term of patent 14 years.

To all whom it may concern:

Be it known that I, JOSEPH L. KALLUS, a citizen of the United States, residing in the borough of Brooklyn, county of Kings, and State of New York, have invented a new, original, and ornamental Design for a Doll, of which the following is a specification, reference being had to the accompanying drawings, forming a part thereof.

In the drawings, Fig. 1 is a front and Fig. 2 is a side view of a doll embodying my design.

I claim:

The ornamental design for a doll, as shown.

JOS. L. KALLUS.
